UNITED STATES PATENT OFFICE

CHARLES HODGETTS, OF BROOKLYN, NEW YORK.

DESIGN FOR A TEA-POT.

Specification forming part of Design No. 5,969, dated July 2, 1872.

To all whom it may concern:

Be it known that I, CHARLES HODGETTS, of Brooklyn, county of Kings, in the State of New York, have produced a new and original Design for Tea and Coffee Pots, of which the subjoined illustration exhibits the nature, &c.

The nature of my design is fully represented in the accompanying drawing.

The body is formed with a broad base, A, tapering slightly toward the top to a line at A', from which it is rounded, as shown at B, forming an ogee, and from this gradually tapering smaller to the line at D', being rounded above, as shown at D. The lid is elevated, rising to a peak, with two furrowed lines divid-

ing the same into three divisions. Thus two full or rounded surfaces, F and H, are presented, with a curved tapering peak, above represented at I, with a knob above.

I am aware of tea and coffee pots with a broad base, tapering to the top; also, of those which are rounded and largest above the base. These I do not claim.

What I claim as my invention is—

A design for a tea and coffee pot, substantially as described and shown.

CHAS. HODGETTS.

Signed in presence of—

SAML. T. WATERHOUSE,
JNO. C. JACKSON.
